(57) **CLAIM**

The ornamental design for an insulated wine glass, as shown and described.

DESCRIPTION

FIG. 1 is a perspective view of an insulated wine glass showing my new design;

FIG. 2 is a front elevation view thereof;

FIG. 3 is a side elevation view thereof;

FIG. 4 is a top plan view thereof;

FIG. 5 is a bottom plan view thereof; and,

FIG. 6 is an exploded view of the insulated wine glass.

The claim to the insulated wine glass is directed to the collective appearance of the articles shown, including a transparent body, transparent interior portion, and lid.

1 Claim, 6 Drawing Sheets
